FRED J. SCHWERK, OF SILVER CREEK, NEW YORK.

MECHANICAL MOVEMENT.

1,318,507.

Specification of Letters Patent.

Patented Oct. 14, 1919.

Application filed April 8, 1918. Serial No. 227,267.

To all whom it may concern:

Be it known that I, FRED J. SCHWERK, a citizen of the United States, residing at Silver Creek, in the county of Chautauqua and State of New York, have invented certain new and useful Improvements in Mechanical Movements, of which the following is a specification.

This invention relates to mechanical movements, and more particularly to a mechanism for producing reciprocatory motion.

One of the main objects of the invention is to provide a mechanism of simple construction and operation by means of which a device may be reciprocated uniformly, this reciprocation being effected automatically. A further object is to provide a mechanism especially adapted for use in connection with separators and similar machines for reciprocating the brush for cleaning the separator screens. Another object is to provide means whereby the amplitude of the reciprocation produced may be readily adjusted so as to suit the particular screen or other object in connection with which the mechanism is used. A still further object is to provide simple and efficient means for shifting the driving mechanism so as to alternate reverse travel of the brush or other objects being reciprocated. Further objects will appear from the detailed description.

In the drawings:

Figure 1 is a front view of a mechanical movement constructed in accordance with my invention, the brush which is to be reciprocated and associated parts being fragmentarily illustrated.

Fig. 2 is a section taken substantially on line 2-2 of Fig. 1.

Fig. 3 is a fragmentary detail of the mounting for the tripping rod.

Supporting standards 1 and 2 are secured to the upper face of a suitable base 3' which, when the mechanism is used in connection with a separator, may be a cross beam of the separator. Standard 1 is provided at its upper end with a bearing sleeve 2^a, which is in axial alinement with a bearing sleeve 2^b at the upper end of standard 2. The standards rotatably support a shaft 3 which is secured against axial movement by means of a collar 4 secured thereon by a set screw 5 adjacent the inner end of bearing sleeve 2^b of standard 2, and a collar 6 which is secured on the shaft by a set screw 7 adja-

cent the inner face of bearing sleeve 2^a of standard 1. By this means the shaft is supported for free rotation in either direction and, by loosening the set screws 5 and 7, 60 the shaft may be moved in either direction axially so as to be removed from the standards for cleaning, repairs or other purposes.

A collar 8 is loosely mounted on shaft 3 adjacent the standard 1 and has its ends 65 provided with oppositely directed teeth which provide the oppositely directed clutch elements 9 and 10. Clutch element 9 is adapted to coöperate with a clutch element 11 formed at the inner end of collar 6 so as 70 to operatively connect sleeve 8 to the shaft. Clutch element 10 is adapted to coöperate with a clutch element 12 formed at the outer end of a sleeve 13 loosely mounted on shaft 3 and carrying at its inner end a miter gear 75 14. The inner face of gear 14 is counter sunk to receive a collar 15 secured on shaft 3, a similar collar 16 being provided at the outer end of sleeve 13. By this means, the sleeve 13 and gear 14 are mounted so as to 80 be freely rotatable on shaft 3, and a wheel 16' is secured to sleeve 8 at the approximate center thereof, and this wheel or pulley 16' may be rotated by means of a belt driven from any suitable source of power. By 85 shifting the sleeve 8 in proper direction rotation may be imparted to shaft 3 through clutch element 11 and collar 6, or sleeve 13 and bevel gear 14, as will be evident.

Miter gear 14 meshes with a horizontally 90 disposed miter gear 17 which is rotatably mounted on a stub shaft 18 carried by a base member 19 mounted on base 3', a suitable spacing collar 20 being interposed between base 19 and the hub of gear 17 so 95 as to rotatably support the gear in proper position. Miter gear 17 also meshes with a miter gear 21 which is fixedly secured to shaft 3 by means of a set screw 22, this latter gear being positioned at the diametrically opposite side of gear 17 from gear 14. By shifting sleeve 8 so as to bring clutch element 9 into operative engagement with element 11, rotation will be imparted to shaft 3 directly from drive pulley 16'. In 100 105 this case, the direction of rotation of shaft 3 will be the same as the direction of rotation of the pulley. If the sleeve 8 is shifted so as to bring clutch elements 10 and 12 into engagement, miter gear 14 will be rotated in the same direction as drive pulley 16', but miter gear 21 will be rotated in the 110

opposite direction being positioned opposite gear 14 diametrically of miter gear 17. By this means, the direction of rotation of shaft 3 may be readily reversed.

5 Shaft 3 is provided with a threaded portion 3^a which extends substantially one-half of the length of the shaft. An internally threaded collar 24 is mounted on this threaded portion of the shaft so as to be 10 moved longitudinally thereof when the shaft is rotated. This collar is provided with an upwardly directed arm 25 which projects to one side of the shaft 3. This arm has a central slot 26 which receives a tripping rod 15 27, the inner end of which is loosely secured to a tripping lever 28 pivotally mounted adjacent its lower end, by means of pivot bolt 29, on a standard 30 secured to base 3'. This tripping rod is slidable through a supporting ring 31 which is rockably mounted 20 for movement about a horizontal axis in the upper end of an arcuate arm 32 secured to the outer end of bearing sleeve 2^b and disposed in alignment with the arm 25 of sleeve 24. The tripping rod is provided with tripping collars 33 adjustably secured thereon by means of set screws 34.

These collars are adapted to be engaged by the arcuate arm 25 of the main tripping 30 collar 24 so as to move the rod 27 longitudinally thus rocking the tripping lever 28 about its axis in either direction depending upon the direction of travel of arm 25. In this manner, the tripping lever may be 35 rocked in either direction so as to bring the weight member 35 which is adjustably secured thereon, by means of a bolt 36 passed through the center of the weight and inserted into any one of the vertical series of 40 apertures 37 provided in the lever for this purpose, beyond the vertical plane of the axis of the bolt 29, thus causing the weight to rock the lever so as to cause operation of the shifting mechanism.

45 Lever 28 is provided, at its lower end, with a laterally projecting pin 38 which extends through a longitudinal slot 39 formed in the inner end portion of a connecting link 40. Slot 39 is cut away at the center 50 of its upper side to produce a contiguous recess 41 which receives the pin 38 when lever 28 is in a substantially vertical or neutral position, this recess providing slight shoulders or abutments adjacent each side 55 of the pin 38 which serve to slightly retard movement of the pin. The outer end of link 40 is pivotally secured, as at 42, to the shank 43 of a shifting fork 44 of usual construction provided at the upper ends of its arms with 60 antifriction rollers fitting into an annular recess or groove 45 provided in sleeve 8. The shank 43 of the fork is pivotally secured by means of a pivot bolt 46, to a standard 47 mounted on the base 3', bolt 65 46 being positioned a slight distance above

the pivot bolt 42 which connects the outer end of link 40 to the lower end of the shank. In this manner, when lever 28 is rocked, the sleeve 8 will be shifted in proper direction so as to operatively connect the drive pulley 70 16' to the shaft 3 so as to cause proper rotation thereof.

In using this mechanism, the brush or other element to be reciprocated may be connected directly to the collar 24 so as to 75 move therewith if desired, or may be connected to the shaft 3 so as to be operated thereby. When the movement is used in connection with a separator or similar machine, I prefer to employ this type of connection, though it will be evident that the article to be reciprocated may be connected to the apparatus in any manner desired. A sprocket wheel 46 is secured on shaft 3 adjacent standard 2. This sprocket wheel is 80 connected by a sprocket chain 47 to a sprocket wheel 48 secured on a screw shaft 49 which may be rotatably supported adjacent the underneath of the screen or element to be cleaned. A brush carriage 50 is 85 inferiorly threaded to receive the shaft 49 and carries the brush 51. A suitable guide strip 52 may be provided for engagement with carriage 50 as to prevent rotary movement thereof with the shaft 49. The pitch of the 90 threads of shaft 49 may be either greater or less than, or the same as, the pitch of the threads of shaft 3, as desired. When the main shaft 3 is rotated, this rotation will be imparted to screw shaft 49 so as to cause 95 movement of the brush carriage 50 longitudinally of the same in one direction. When the direction of rotation of shaft 3 is reversed, the carriage 50 will be caused to move longitudinally of shaft 49 in the 100 opposite direction. This reversal of the direction of rotation of the main shaft 3 is effected by engagement of the tripping collars 33 by the arm 25. These collars are 105 set such a distance apart that they will engage arm 25 when the brush carriage 50 has been moved in either direction a distance corresponding to the width of the screen to be cleaned. With the clutch elements 10 and 12 in engagement, the shaft 110 3 will be rotated in such direction as to cause movement of collar 24 and arm 25 carried thereby toward the tripping lever 28. When arm 25 engages the inner collar 33, tripping rod 27 will be moved longitudinally 115 toward the drive pulley 16'. This results in swinging the lever 28 about its axis toward the guide pulley. When the lever has been moved into substantially vertical position, pin 38 engages into the recess 41 of link 40 and is frictionally held therein. As the pressure on lever 28 increases, the pin 38 is forced out of recess 41 and lever 28 is moved so as to bring the center of weight 120 35 beyond the vertical plane of the axis of 130

bolt 29. The weight then acts to swing the lever in such direction as to bring the pin 38 into comparatively violent contact with the link 40 at the inner end of the slot 39. 5 This results in moving the link 40 inward which causes the fork 44 to be rocked outward so as to shift sleeve 8 toward standard 1 and bring the clutch elements 6 and 11 into operative engagement. In this manner, the 10 shaft is connected directly to the guide pulley 16' so as to rotate therewith, the direction of rotation of the shaft being thus reversed so as to reverse the direction of travel of the collar 24. When the collar 15 reaches its extreme position in the other direction, arm 25 engages tripping collar 33 at the other side of the arm so as to rock lever 28 and return it to its original position thus again reversing the direction of rotation 20 of the shaft. In this manner, the direction of rotation of shaft 3 is automatically reversed at predetermined times, and this causes the reversal of the direction of rotation of screw shaft 49 thus reciprocating 25 brush carriage 50 and the brush 51 carried thereby. As the shifting or trip collars 33 may be readily adjusted longitudinally of the tripping rod 27, the distance apart of these collars may be readily varied to suit 30 the distance of travel of the carriage 50. Of course as previously stated, if desired, the brush or other member which it is desired to reciprocate may be connected directly to the carriage or collar 24 so as to be moved 35 directly thereby, thus doing away with the supplemental shaft 49 and associated parts. This shaft 49 and the members associated therewith have been illustrated merely as showing one way of using the mechanism, 40 but it is to be understood that I do not intend to in any way limit myself to this one particular use as this mechanism may be utilized to cause either direct or indirect reciprocation of any article to which it is 45 desired to impart such motion.

To prevent unnecessary strain being placed upon the link 40 and the shifting fork, I provide stop collars 53 at each side of arm 32, these collars being adjustably secured to tripping rod 27 by set screws 54. 50 The collars 53 are so adjusted as to engage arm 32 when lever 28 has been rocked into its extreme position in either direction and the shifting operation has been completed. 55 In this manner, the weight of lever 28 and the shift weight 35 carried thereby is supported by the stop collar 53 which is in engagement with arm 32 thus relieving the link 40 and shifting fork of the strain incident to supporting this weight.

The foregoing description and the drawings have reference to what may be considered the preferred, or approved, form of invention. It is to be understood that I may 60 make such changes in construction and ar-

rangement and combination of parts, materials, dimensions, etc., as may prove expedient and fall within the scope of the appended claims.

Having thus fully described my invention, 70 what I claim as new and desire to secure by Letters Patent, is:

1. In a mechanical movement, a rotatable shaft screw threaded for a portion of its length, a collar mounted on the screw 75 threaded portion of the shaft and interiorly threaded so as to be moved longitudinally on the shaft when said shaft is rotated, a drive pulley, clutch elements carried by said drive pulley, a clutch element secured to 80 said shaft and engageable by one of the clutch elements carried by the drive pulley so as to impart rotation to the shaft directly from said pulley, gearing connected to said shaft for causing rotation thereof in 85 a direction reverse to the direction of rotation of the drive pulley, said gearing being provided with a clutch element engageable by the other clutch element carried by the pulley, shifting means for moving the pulley 90 in such direction as to operatively connect the same directly to the shaft or to the reversing gearing, and means controlled by the collar operable on the shaft for operating said shifting means so as to reverse the 95 direction of rotation of the shaft when the collar has been moved a predetermined distance longitudinally thereof in either direction.

2. In a mechanical movement, a rotatable 100 shaft threaded for a portion of its length, a collar mounted on the threaded portion of said shaft so as to be moved longitudinally thereof when the shaft is rotated, a pulley loosely mounted on said shaft for independent rotation and provided at its opposite sides with clutch elements, a clutch element secured to the shaft and adapted to be engaged by one of the clutch elements carried by the pulley so as to directly connect the 105 pulley to the shaft to cause rotation thereof in the direction of rotation of the pulley when said pulley is rotated, reversing gearing connected to the shaft so as to cause rotation thereof in the reverse direction to 110 the direction of rotation of the pulley when the pulley is operatively connected to said reversing gearing, the reversing gearing being provided with a clutch element adapted to be engaged by the other clutch element 115 of the pulley so as to operatively connect the pulley thereto, a shifting fork connected to the pulley for moving the same longitudinally of the shaft so as to bring either of the clutch elements carried thereby into 120 operative engagement with either the clutch element secured to the shaft or the clutch element carried by the reversing gearing, a rockably mounted reversing lever, a slidably mounted tripping rod loosely secured 125 130

to said lever so as to rock the same when the rod is moved longitudinally, an arm carried by the collar and extending about said tripping rod, tripping collars secured 5 on the rod at each side of said arm and engageable thereby so as to cause longitudinal movement of the rod when the collar has been moved a predetermined distance in either direction longitudinally of the shaft,

and connections between the fork and the 10 tripping lever for operating said fork when the lever is rocked.

In testimony whereof I affix my signature in presence of two witnesses.

FRED J. SCHWERK.
